Inventor:

Benjamin H. Anibal

By Blackmore, Spencer & Reid
Attorneys.

UNITED STATES PATENT OFFICE.

BENJAMIN H. ANIBAL, OF PONTIAC, MICHIGAN, ASSIGNOR TO GENERAL MOTORS CORPORATION, OF DETROIT, MICHIGAN, A CORPORATION OF DELAWARE.

DESIGN FOR A COMBINED AUTOMOBILE HOOD AND RADIATOR.

Application filed August 9, 1926. Serial No. 18,654. Term of patent 14 years.

To all whom it may concern:

Be it known that I, BENJAMIN H. ANIBAL, a citizen of the United States, and a resident of Pontiac, county of Oakland, and State of Michigan, have invented a new, original, and ornamental Design for a Combined Automobile Hood and Radiator, of which the following is a specification, reference being made to the accompanying drawing, forming a part thereof.

In the drawing:

Figure 1 is a perspective showing of my new design.

Figure 2 is a front elevation.

I claim:

The ornamental design for a combined automobile hood and radiator, as shown.

BENJAMIN H. ANIBAL.
